UNITED STATES PATENT OFFICE.

KRAFT BOOTH, OF PHILADELPHIA, PENNSYLVANIA, ASSIGNOR TO
GILLINDER & SONS, INC., OF PHILADELPHIA, PENNSYLVANIA.

DESIGN FOR AN ARTIFICIAL-LIGHT REFLECTOR.

SPECIFICATION forming part of Design No. 37,424, dated May 2, 1905.

Application filed March 9, 1905. Serial No. 249,283. Term of patent 7 years.

To all whom it may concern:

Be it known that I, KRAFT BOOTH, a citizen of the United States, and a resident of the city of Philadelphia, in the county of Philadelphia and State of Pennsylvania, have invented a new, original, and ornamental Design for an Artificial-Light Reflector, of which the following is a specification, reference being had to the accompanying drawings, in which—

light reflector, showing my design. Fig. 2 is a top or plan view of the same.

I claim as my invention—

The ornamental design for an artificial-light reflector, as shown.

KRAFT BOOTH.
